DESIGN.

I. G. HATCHER.
BURIAL CASKET.

No. 15,341.

Patented Aug. 26, 1884.

UNITED STATES PATENT OFFICE.

ISAIAH G. HATCHER, OF CLEVELAND, OHIO.

DESIGN FOR A BURIAL-CASKET.

SPECIFICATION forming part of Design No. 15,341, dated August 26, 1884.

Application filed February 12, 1884. Term of patent 14 years.

To all whom it may concern:

Be it known that I, ISAIAH G. HATCHER, a citizen of the United States, residing at Cleveland, in the county of Cuyahoga and State of Ohio, have invented and produced a new and original Design for Burial-Caskets, of which the following is a specification, reference being had to the accompanying drawing, forming part therof.

10 The accompanying drawing represents my burial-casket in side elevation.

A represents the body of the casket, of any approved form, encircled at its base and at its upper edge with ornamental bands or moldings B. The cover C is of raised work throughout its entire surface, which gives it a bold, massive, and striking appearance which is unique in burial-caskets. This raised work does not terminate too abruptly, but slopes 15 downwardly from the panels D in graceful lines, the general sweep of which should be crowning or convex rather than concave. The cover is provided about midway up the 20 sloping edge with an ornamental band or molding, E, which adds to the general appearance of the parts. In a cover constructed as above no ledge is left for thumb-screws or other fasteners, and hence, when secured on the body of the casket, presents a neat and finished appearance.

I would have it understood that I do not restrict myself to any particular design for ornamenting the bands or moldings Band E, but consider myself at liberty to change or alter the same without departing from my invention.

What I claim is—

1. In a design for a burial-casket, a cover of raised work, the outer edges of which are sloped downwardly and outwardly, and provided about midway said sloping portion with an ornamental band, substantially as set forth.

2. A design for burial-caskets, consisting of a cover composed of raised work, the edges of said cover sloping downwardly and outwardly, as described, and terminating in a line with the casket-body, and ornamented bands encircling the sloping edges of the cover and the base and upper edge of the casket-body, substantially as set forth.

In testimony whereof I have hereunto set my hand, in the presence of two subscribing witnesses, this 2d day of February, A. D. 1884.

ISAIAH G. HATCHER.

Witnesses:

CHAS. H. DORER,
ALBERT E. LYNCH.
